Primary Examiner — Rosemary K Tarcza(74) *Attorney, Agent, or Firm* — Justin Lampel(57) **CLAIM**

The ornamental design for a charging head, as shown and described.

DESCRIPTION

FIG. 1 is a perspective view of a charging head showing the claimed design;

FIG. 2 is a top plan view thereof;

FIG. 3 is a left side view thereof;

FIG. 4 is a rear elevational view thereof;

FIG. 5 is a right side view thereof;

FIG. 6 is a front elevational view thereof; and,

FIG. 7 is a bottom plan view thereof.

The broken lines illustrate portions of the charging head that form no part of the claimed design.

1 Claim, 7 Drawing Sheets(56)
